SHORT-TRAVERSE MECHANISM FOR
BOBBIN WINDING MACHINESGlover C. Joyce, Worcester, Mass., assignor to
Whitin Machine Works, Whitinsville, Mass., a
corporation of Massachusetts

Application December 8, 1951, Serial No. 260,720

6 Claims. (Cl. 242—27)

1

This invention relates to the winding of bobbins to be used in automatic weft-replenishing looms. It is desirable that such bobbins be provided with a predetermined number of short-traverse windings before the regular full-traverse winding is started. Such short-traverse windings provide sufficient thread in storage on the bobbin so that the thread remaining on a bobbin which is indicated for replenishment will not be exhausted before bobbin transfer takes place.

It is the general object of my invention to provide improved and relatively simple mechanism for producing short-traverse for the initial windings on a bobbin.

A further object is to provide improved means for determining the amount or yardage of thread to be placed in the short-traverse windings.

My invention further relates to arrangements and combinations of parts which will be herein-after described and more particularly pointed out in the appended claims.

A preferred form of the invention is shown in the drawings, in which

Fig. 1 is a plan view of my improved bunch-building mechanism;

Fig. 2 is a front elevation thereof;

Fig. 3 is a left-hand end view thereof;

Fig. 4 is an exploded perspective and partly diagrammatic view of the mechanism;

Figs. 5, 6 and 7 are detail sectional views, taken along the lines 5—5, 6—6 and 7—7 in Fig. 2; and

Fig. 8 is a detail sectional view, taken along the line 8—8 in Fig. 1.

Referring to the drawings, I have shown my improved bunch-building mechanism mounted on the frame of a winding machine W in which a bobbin B is mounted for high speed rotation by a driving spindle S. The thread or yarn Y is held on the bobbin by a thread guide G, which is normally oscillated between the limits shown in full and broken lines in Fig. 1.

The thread guide G is mounted in a lever 10 which is pivoted in a thread guide carriage C and which is oscillated by driving mechanism not shown.

It is the general object of the present invention to provide means for limiting the traverse of the thread Y while the winding machine is applying the first few windings or layers of thread at the butt of the bobbin B.

For this purpose, I provide a guide-wire 12 (Fig. 1) mounted in a bell crank 14 which is pivoted at 15 on a fixed stud 16. When the guide-wire 12 is in the broken-line position shown in Fig. 1, the thread guide G lays the thread Y on

the bobbin for the full traverse of the thread guide, but when the guide-wire 12 is in the full-line position shown in Fig. 1, the winding is limited to a short traverse adjacent the butt of the 5 bobbin B, as most clearly indicated in Fig. 2.

It will be understood that the normal or full swing of the thread guide G is unchanged by the operation of the bunch-building mechanism, but that for short-traverse the thread or yarn Y 10 is confined as indicated at Fig. 2, so that it cannot follow the thread guide as the guide swings to the extreme left in Fig. 2 or away from the butt of the bobbin B.

The thread-engaging part of the guide-wire 12 15 (Fig. 1) is inclined with respect to the axis of the bobbin spindle S when the guide-wire is in operative position. This is important, as it prevents the initial windings from being piled up at one point on the bobbin and thus provides 20 a more uniform bunch.

I will now describe my improved mechanism 25 by which the guide-wire 12 is swung into and out of operative position, and by which the period of short-traverse winding is conveniently predetermined.

Referring particularly to Figs. 1 and 2, the bell 30 crank 14 has a pin-and-slot connection to a plunger 20 mounted in the fixed frame of the winding machine W and supporting a spring 22 by which the plunger 20 is normally moved to the right in Fig. 1 to position the guide-wire 12 35 in its inoperative or broken-line position.

The end of the plunger 20 is engaged by the 40 head 24 of an arm 25 mounted on a short shaft 26 (Fig. 4) which is rotatably supported in a fixed plate 27 and which is mounted in parallel relation to a timing shaft 30. A lever 33 (Figs. 4 and 6) is loosely mounted on the end of the short shaft 26 and has an upstanding arm 34 which is 45 yieldingly held against a lug on a short arm 36 (Fig. 6) which is fixed to the short shaft 26. A spring 38 (Fig. 4) holds the parts 34 and 36 normally in yielding engagement but will yield if the arm 34 is rocked too far.

When the lever 33 is rocked, the arm 34 associated with the lever will be swung anti-clockwise as viewed in Fig. 4, and will correspondingly move the arm 36, the shaft 26 and the arm 25 to shift the plunger 20 to the left in Figs. 1 and 4 50 and to thereby swing the guide-wire 12 to operative or full-line position to limit the thread traverse. The rocking of the lever 33 to thus operatively position the guide-wire 12 is effected by a cam 40 (Figs. 2 and 3) on a cam shaft 41 which 55 is normally stationary but which is released to

make a single revolution whenever the winding machine is stopped for bobbin-replacement.

The mechanism controlling the intermittent rotation of the shaft 41 and the cam 40 is not disclosed herein, as it forms no part of the present invention. The connection between the cam 40 and the lever 33 includes a link 42 and a bell crank 43. With the described connections, the guide-wire 12 will be moved to operative or full-line position whenever the raised portion 40a of the cam 40 moves under the end of the bell crank 43.

A circular disc 50 (Fig. 4) is mounted on the timing shaft 30 and has a notched shoulder 51 normally engaging the upper end of the arm 36 previously described. When the arm 36 is swung outward by the rocking of the lever 33, the disc 50 and the timing shaft 30 are free to be rotated anti-clockwise by a spiral spring 54 (Figs. 4 and 8) having its inner end secured to the shaft 30 and its outer end secured to a fixed stud or other support 55.

Whenever the disc 50 is released, the disc 50 and shaft 30 are thus rotated anti-clockwise until a pin 57 (Fig. 4) in the disc 50 engages an arm 58 which is held in normal fixed position by a pin 60 inserted in a selected hole 61 (Figs. 4 and 2) in a circular series of such holes arranged in the plate 27 and concentric with the shaft 30.

Special provision is made for rewinding the spring 54 after each release of the timing shaft 30 and disc 50. For this purpose, a rod 65 (Fig. 4) is mounted parallel to and adjacent the timing shaft 30 and loosely supports a gear 66 and associated pinion 67.

The gear 66 has a driving connection (not shown) with the spindle S, so that the gear 66 is continuously rotated whenever the spindle S and bobbin B are rotated. An arm 68 is fixed to the rod 65 and supports a short shaft 69 having a gear 70 engaging the pinion 67 and having a fine-tooth pinion 71 engageable with a relatively large fine-tooth gear 72 on the timing shaft 30. A second arm 75 is fixed on the rod 65 and supports a swivel block 76 through which extends a bolt 77 having a head 78 pivoted at 79 to the free or swinging end of the lever 33. A spring 80 presses the block 76 against a nut 82 threaded on the outer end of the bolt 77.

When the lever 33 is swung upward about the axis of the shaft 26 by engagement of the lever 33 (Fig. 2) by the cam lug 40a, such action rocks the rod 65 and causes the fine-tooth pinion 71 to momentarily engage the gear 72. This occurs at the moment when the toggle formed by the lever 33 and the bolt 77 is straightened. At the same time, the lever 33 swings the arms 34 and 36 outward to release the disc shoulder 51. This preliminary engagement of the pinion 71 and the gear 72 has no significance.

As the lever 33 continues to swing upward, it again shortens the toggle. The pinion 71 is thus withdrawn from the gear 72 and the spring 54 on the timing shaft 30 can then rotate said shaft anti-clockwise until the stop pin 57 engages the normally fixed stop arm 58.

As soon as the cam projection 40a (Fig. 2) has passed beyond the end of the bell crank 43, the lever 33 (Fig. 4) is free to start downward, thus allowing the arm 36 to contact the periphery of the disc 50. This downward movement also straightens the toggle 33-77, so that the gear 72 is operatively engaged by the pinion 71. The toggle is then held straightened until the driving pinion 71 rotates the gear 72, shaft 30 and disc 75

50 clockwise far enough so that the arm 36 can drop off the shoulder 51.

The lever 33 then completes its return or downward movement to initial position and the pinion 71 is again disengaged. A spring 85 (Fig. 2) may be provided to assist this disengaging movement.

At the same time, the arm 25 on the shaft 26 is moved clockwise to withdraw the plunger 28 and to thereby allow the guide-wire 12 to swing to inoperative or broken-line position.

General operation

The general operation of my improved bunch-building mechanism may be deduced from the foregoing detailed description but may be briefly restated as follows:

When the winding of a bobbin B has been completed, rotation of the spindle S is automatically stopped to permit replacement of the bobbin. At the same time, the cam shaft 41 is started for a single rotation and such rotation brings the cam projection 40a under the bell crank 43. The bell crank then acts through the link 42 to swing the lever 33 upward or anti-clockwise. This partially rotates the shaft 26, causing the plunger 28 to shift the guide-wire 12 to operative or full-line position. At the same time the notched disc 50 is released, so that the spring 54 may rotate the timing shaft 30 anti-clockwise until the stud 57 on the notched disc 50 engages the adjustable stop arm 58. The cam projection 40a then releases the bell crank 43 and lever 33 and allows the lever 33 to shift the pinion 71 into engagement with the gear 72 on the timing shaft 30.

The parts remain in this position until the spindle S and bobbin B are automatically started in rotation to wind the bobbin. Thereupon the pinion 71 will also be started to rotate and will rotate the gear or disc 72 and the timing shaft 30 clockwise until these parts have been returned to their original position. The arm 36 will then be swung in under the shoulder 51 by the spring 85, and the parts will be returned to initial position with the pinion 71 out of engagement with the gear 72.

The length of time between the starting of the spindle S and bobbin B in rotation to wind the bobbin, and the withdrawal movement of the guide-wire 12 is determined by the setting of the stop arm 58, which may be varied some 25° by selecting different holes 61 for insertion of the stop arm pin 60. The yardage of thread or yarn to be placed in the initial short-traverse winding or bunch on the bobbin may thus be variably and accurately controlled, as the additional length of thread or yarn for each adjustment step of the stop arm 58 may be readily predetermined.

One form of mechanism which may be used to give the cam shaft 41 a single revolution on spindle stoppage is shown in my copending application, Serial No. 260,719, filed December 3, 1951, issued February 23, 1954, as Patent No. 2,670,147.

Having thus described my invention and the advantages thereof, I do not wish to be limited to the details herein disclosed, otherwise than as set forth in the claims, but what I claim is:

1. A short-traverse mechanism for a bobbin-winding machine having a rotated bobbin spindle and a regularly oscillated thread guide associated with said spindle, which comprises a guide-wire movable into the traversing path of the thread for short traverse, means to move said guide-wire to operative position and to maintain said wire in fixed operative position for a predetermined period, and automatic means to terminate

the period during which said guide-wire remains in fixed operative position in predetermined respect to the number of spindle revolutions after such positioning of said guide-wire.

2. A short-traverse mechanism for a bobbin-winding machine having a rotated bobbin spindle and a regularly oscillated thread guide associated with said spindle, which comprises a guide-wire movable into the traversing path of the thread for short traverse, means to move said guide-wire to operative position, a segmental circular timing disc effective when released and displaced from initial position to hold said guide-wire in said operative position, means to release said disc when said guide-wire is moved to said operative position, means to give said disc a predetermined angular setting movement as soon as it is released and while the bobbin spindle is at rest, means to thereafter return said disc at a predetermined speed to initial position and to thereby free said guide-wire for return to inoperative position, and means to return said guide-wire to inoperative position when thus released.

3. The combination in a short-traverse mechanism as set forth in claim 2, in which the predetermined setting of the timing disc is effected automatically while the bobbin spindle is at rest.

4. The combination in a short-traverse mechanism as set forth in claim 2, in which the predetermined setting of the timing disc is effected automatically while the bobbin spindle is at rest, and in which the return movement of the timing disc to initial position begins simultaneously with the restarting of the bobbin spindle.

5. The combination in a short-traverse mechanism as set forth in claim 2, in which a normally-fixed stop limits the setting movement of said timing disc, and in which manual means is provided for setting said stop.

6. A short-traverse mechanism for a bobbin-winding machine comprising a winding spindle, a thread guide, means to give said thread guide full-traverse oscillations, auxiliary means to restrict the thread travel to short but definite traverse movements while said thread guide continues its full-traverse movements, a device to maintain said auxiliary means in operative position for a period predetermined with respect to the number of spindle revolutions, and means to return said device to normal inoperative position before bobbin-winding begins, and said latter means comprising a timing disc normally held in an initial position and means releasable on completion of bobbin-winding and effective to automatically advance the auxiliary travel-restricting means to operative position, to release the timing disc for automatic rotational movement to a predetermined angular position, and to complete a driving connection between the winding spindle and said timing disc, and said disc being thereafter progressively returned to its initial position by said driving connection during a predetermined winding period of the bobbin and thereon releasing the travel-restricting means for return to its inoperative position.
